United States Patent Office.

MARCUS M. AMMIDOWN, OF BOSTON, MASSACHUSETTS.

Letters Patent No. 82,674, dated October 6, 1868.

IMPROVED MODE OF TRANSMITTING MOTION.

The Schedule referred to in these Letters Patent and making part of the same.

Be it known that I, MARCUS M. AMMIDOWN, of Boston, in the county of Suffolk, and State of Massachusetts, have invented a new and improved Mode of Transmitting Motion, of which the following is a full, clear, and exact description, reference being had to the accompanying drawings, making a part of this specification, in which—

Figure 1 represents a vertical longitudinal section of a device embodying my invention.

Figure 2 is a side elevation of the same.

Figures 3 and 4 are transverse sections, on the line *x y* of fig. 1, showing the different positions of the V-shaped pawl in relation to the toothed wheel.

Figures 5 and 6 are detail views of the spring which is attached to the V-shaped pawl.

The nature of my invention consists in a mode of transmitting motion, by means of a V-shaped pawl, in combination with a toothed wheel, the spaces between the teeth of which conform to the point of the said pawl, the latter being arranged within a shell, a portion of which is made eccentric to the toothed wheel or shaft upon which the wheel is fixed, so that, as the shell is turned upon a separate hub or shaft which holds the gear-wheel or pulley from which it receives its motion, the eccentricity of the shell will cause the V-shaped pawl to engage with or be released from the toothed wheel, and thus impart motion to the shaft whenever required.

Referring to the drawings, *s* represents a shaft, to which it may be desirable to transmit motion, and is arranged in a frame in any suitable manner.

a is a hub, surrounding the shaft, and fitted loosely on the same, so as to allow a free rotation to the shaft.

c is a gear-wheel, attached to or forming a part of the said hub, and is made to rotate by means of the worm-gear *b*, by the application of any suitable power.

Surrounding the hub *a*, and fitting snugly on the same, but so as to admit of a free rotary motion, is a shell, *d*, extending below the hub *a* a short distance, as from *i* to *k* in fig. 1. The hub *a* is made concentric with the shell *d*.

At the lower end of the hub *a* is attached a pawl, *e*, made with a V-shaped inner edge, as shown in figs. 3 and 4, and extending downwards to the lower end of the shell *d*. The pawl *e* is allowed a limited motion towards and from the centre of the shaft, and attached to it is a curved spring, *g*, as seen in fig. 5, inserted in a recess in the hub *a*, which serves to force the pawl away from the toothed wheel *f*. Instead of the curved spring, the pawl may extend upwards in a recess in the hub *a*, and be pressed out by a straight spring arranged within the recess.

The space in the lower portion of the shell *d*, in which the pawl *e* is fitted, is made eccentric to the portion above and to the shaft *s*, as seen in figs. 3 and 4. Within this eccentric-space is also arranged a toothed wheel, *f*, fixed to the shaft *s*.

The eccentricity of the lower portion of the sleeve *d* is such that upon being rotated the pawl will be forced into or out of contact with the toothed wheel *f*, as desired, and thus communicate or transmit motion to the shaft *s* at pleasure.

The spaces between the teeth of the wheel *f* are made to conform to the wedge-shaped point of the pawl, and thus serve to force the latter out of gear with the wheel when the pressure exerted by the eccentric is removed from the pawl.

The pawl may at any time be readily thrown in or out of gear with the toothed wheel, thus transmitting motion to the shaft, or stopping the same at any moment desired.

The device is particularly applicable in all machines where a feed-motion is required.

Having thus described my invention, what I claim as new, and desire to secure by Letters Patent, is—

1. The combination of the hub *a* and the cylindrical shell *d*, provided with the eccentric, *d'*, substantially as and for the purpose set forth.

2. The combination, with the eccentric, *d'*, of the pawl *e* and toothed wheel *f*, substantially as and for the purpose specified.

In testimony whereof, I have signed my name to this specification in the presence of two subscribing witnesses.

M. M. AMMIDOWN.
